Jerome F. Sherbino
By his Attorney Oscar Geier

UNITED STATES PATENT OFFICE.

JEROME F. SHERBINO, OF MOUNTAIN LAKES, NEW JERSEY.

TIMER FOR INTERNAL-COMBUSTION ENGINES.

1,391,984.

Specification of Letters Patent. Patented Sept. 27, 1921.

Application filed October 15, 1919. Serial No. 330,818.

To all whom it may concern:

Be it known that I, JEROME F. SHERBINO, a citizen of the United States, residing at Mountain Lakes, county of Morris, and State 5 of New Jersey, have invented certain new and useful Improvements in Timers for Internal-Combustion Engines, of which the following is a specification.

This invention relates to timers for internal combustion engines, being intended 10 more particularly for use on multi-cylinder engines.

The invention has for an object to provide a timer characterized by extreme simplicity 15 of construction and efficiency of operation, and by an arrangement of parts acting to protect the electrical conductors and contact members.

For further comprehension of the invention 20 and of the object and advantages thereof, reference will be had to the following description and accompanying drawings, and to the appended claim in which the various novel features of the invention 25 are more particularly set forth.

Figure 1 of the drawings is a part side elevation and part axial section of a timer constructed according to my invention.

Fig. 2 is a horizontal section on the line 30 2-2 of Fig. 1.

The contact members of my improved timer are inclosed within a cylindrical casing 1 which is open at one end and is closed at its opposite end by an integral cap portion 2 of flattened conical form. As shown 35 in Fig. 1 the outer conical surface of the cap forms a greater angle with the axis of the cap, than the inner conical surface, so that the conical wall of this cap tapers in thickness from bottom to top, being of much greater thickness at the bottom than the cylindrical wall 1, thus providing an annular surface 3 in a plane transverse to the axis of the casing.

45 This surface provides a runway for the rotating contact of the timer, which contact

here comprises a stud 4 slidable in a socket 5 formed in a head 6 on the end of an arm 7 secured by any suitable means to the usual shaft 8, a spring 9 in the socket 5 pressing 50 the stud outward.

Carried by the cap portion 2 are a series of fixed contacts each consisting of a flat segmental plate 10 set into the face 3 flush therewith and evenly spaced therearound. 55 These plates are formed with studs 11 which project through the cap 2 parallel to the axis thereof and terminate in screws 12 providing binding posts.

As will be understood the casing is formed 60 of insulating material and in constructing the same I prefer to mold the fixed contacts therein. For adjustment of the casing in the usual manner to change the timing I secure a bracket 13 by screws 14 to the outside of the casing, this bracket having a sleeve 15 adapted to receive the usual adjusting means.

As will be apparent I have provided an exceedingly simple construction and arrangement which provides for ready leading 70 of the wires and for proper inclosing of the moving contact member.

I claim—

A timer comprising a conical cap having 75 conical inner and outer surfaces, the said outer surface forming a greater angle with the axis of the cap than said inner surface, so that said surfaces will diverge toward the base of the cap and will give the wall of the 80 cap a thickness decreasing gradually toward the apex of the cap, the base of the cap having an internal surface transverse to said axis and contact members at said surface, and a casing extending from the outer portion of said base in the direction opposite to the cap, at a greater distance from the axis 85 than said contact members.

In testimony whereof I have affixed my signature.

JEROME F. SHERBINO.
